CARTON

George V. Thompson, Winfield, Ill., assignor to Ferguson-Lander Box Company, a corporation of Illinois
Filed Apr. 4, 1960, Ser. No. 19,827
1 Claim. (Cl. 229—39)

This invention relates to a collapsible carton and more particularly to such a carton which is easily erected and in which the bottom has flaps formed for positive interlocking to maintain the bottom closed and the carton in its erect condition.

An object of this invention is to provide a new and improved bottom flap construction for a carton in which the locking of the bottom is more positively maintained.

Another object of this invention is to provide a carton having a plurality of interconnected side walls with each side wall having a bottom flap and with one pair of opposed bottom flaps each having a diagonal score line forming each of the flaps into an inner part and an outer part with an adhesion portion, each of the adhesion portions attached to an adjacent bottom flap of a second pair of bottom flaps, one of said outer parts having a hook portion and an opposed bottom flap of the other pair having a projecting coplanar tab whereby erection of the carton causes the tab and hook to travel toward each other with the tab passing into a slit adjacent the hook to lie behind the hook and with said hook and tab lying in substantially the same plane when the carton is erected to have abutment therebetween, said abutment occurring to one side of a diagonal between opposed corners of the carton whereby forces tending to collapse the carton maintain said abutment.

Further objects and advantages will become apparent from the following detailed description taken in connection with the accompanying drawings in which:

FIG. 1 is a fragmentary plan view of the one-piece blank with the side of the blank forming the interior of the carton uppermost.

FIG. 2 is a view similar to FIG. 1 showing initial folding of the bottom flaps preparatory to securing thereof;

FIG. 3 is a plan view of the completed carton formed from the blank and shown in collapsed condition;

FIG. 4 is an elevational view looking toward the bottom of the carton and showing the carton in an intermediate position during erection thereof;

FIG. 5 is a perspective view looking toward the bottom of the carton showing the carton in erected condition; and

FIG. 6 is a horizontal section taken generally along the line 6—6 in FIG. 5.

While this invention is susceptible of embodiments in many different forms, there is shown in the drawings and will herein be described in detail an embodiment of the invention with the understanding that the present disclosure is to be considered as an exemplification of the principles of the invention and is not intended to limit the invention to the embodiment illustrated. The scope of the invention will be pointed out in the appended claims.

As shown in the drawing, a paperboard blank indicated generally at 10 has a plurality of side walls indicated at 11, 12, 13 and 14 which are scoringly connected along score lines 15, 16 and 17. The side flap 11 has a sealing flap 20 scoringly connected thereto along a scoreline 21 whereby the carton may be formed from the blank by attachment of the sealing flap 20 to the underside of the side wall 14 and as shown in FIG. 3.

The side walls 11, 12, 13 and 14 each carry parts of structure for closing the top of the carton after it is erected and filled. This structure is shown in FIG. 3 in

2

which the side walls 11 and 13 each carry top flaps 22 and 23, respectively, and the side walls 12 and 14 each carry a top flap 24 and 25, respectively, with the top flap 24 having a hook 26 co-acting with a slit 27 cut in the top flap 25 for closing and locking the top flaps together with the flaps 22 and 23 therebeneath.

The side walls 11 and 13 each carry a bottom flap 30 and 31 scoringly connected thereto by score lines 32 and 33, respectively. The bottom flaps 30 and 31 are spaced 10 from each other with a bottom flap 34 positioned therebetween and scoringly connected to a side wall 12 by a score line 35. The bottom flap 34 along with another bottom flap 36 which is connected to the side wall 14 by a score line 37 form a first pair of bottom flaps 15 which are opposed to each other as the carton is erected. The bottom flaps 30 and 31 constitute a second pair of bottom flaps.

Each of the bottom flaps 34 and 36 of the first pair of flaps has a diagonally extending score line 38 and 39, 20 respectively, which divide each of the flaps into two parts. The bottom flap 34 has inner part 40 and an outer part 41 with an adhesion portion while the bottom flap 36 has an inner part 42 and an outer part 43 with an adhesion portion.

25 In forming the carton from the blank 10, an initial step is illustrated in FIG. 2 in which the bottom flaps 30 and 31 are turned downwardly and the bottom flaps 34 and 36 are also turned downwardly with the adhesion portions of the outer parts 41 and 43 turned upwardly 30 along the diagonal score lines 38 and 39 respectively. The sealing flap 20 is then brought around to seal against the underside of the side wall 14 and at the same time the adhesion portion of part 41 of the bottom flap 34 is secured to the upper side of the bottom flap 30 as 35 viewed in FIG. 2 and the adhesion portion of part 43 of the bottom flap 36 is secured to the upper side of the bottom flap 31 as viewed in FIG. 2. This is accomplished by known gluing operations and results in the collapsed carton shown in FIG. 3 ready for subsequent filling upon erection thereof.

The resulting association of bottom flaps is seen from examination of FIG. 4 in which the carton is partially erected and in which pressure exerted at the score lines 15 and 17 is causing closure of the bottom of the carton 45 by movement of the flaps 30 and 31 toward each other and to a relationship overlying each other across the bottom of the carton. This action is obtained by the bottom flap 36 tending to move towards a flap position which pulls the bottom flap 31 toward the bottom of the carton 50 and the bottom flap 34 moving also to a generally flat condition which pulls the bottom flap 30 toward the bottom of the carton. With the bottom of the carton closed, the bottom flaps are disposed as shown in FIGS. 5 and 6. With the carton in upright condition, the bottom flap 30 55 is beneath the bottom flap 31 and the latter flap extends across the entire bottom of the carton to form a complete closure therefor.

In order to lock the bottom flaps in position and maintain the carton in erect condition, means are provided on 60 the bottom flaps 30 and 36 including a hook 50 formed at the extremity of the outer part 43 of the bottom flap 36 and having a slit 51 adjacent thereto with the part of the blank material at the side of the slit remote from the hook being free of adhesion from the bottom flap 31. 65 This means also includes an integral tab 52 extending beyond the periphery of the bottom flap 30 in coplanar relation therewith and having slightly rounded corners with a substantially straight edge 53.

70 As the carton is being erected as viewed in FIG. 4, the tab 52 is caused to move toward the hook 50 and the tab 52 will pass above the hook 50 and through the slit

51 since the part of bottom flap 36 adjacent to the slit is free of adherence to the bottom flap 31 which tends to open the slit. With the carton bottom finally closed as viewed in FIGS. 5 and 6, the tab 52 extends to the side of the slit 51 opposite from the hook 50 and the relatively straight edge 53 of the tab abuts against the edge of the hook 50. This abutment is maintained effective by the generally coplanar relation between the tab 52 and the hook 50 since the hook 50 lies beneath the outer part 41 of the bottom flap 34 and is thus substantially in the same plane as the tab 52. The tab also extends beyond the base of the slit. This abutment also is to one side of a diagonal between opposite corners of the carton whereby forces tending to collapse the carton maintain the locked relation between the tab 52 and the hook 50.

I claim:

A collapsible carton having a self-locking bottom closed and automatically locked upon erection of the carton comprising, four connected side walls with each wall having a scoringly connected bottom flap, the first and second of said bottom flaps forming a first pair of opposed bottom flaps each having a diagonal score line forming the flaps into an inner part and an outer part with an adhesion portion, the third and fourth of said bottom flaps forming a second pair of opposed bottom flaps, each being adhesively secured to one adjacent adhesion portion of said first pair of opposed bottom flaps, said third bottom

5 flap of the second pair having a planar projecting tab located intermediate the ends of the free edge of the flap and extending beyond the remainder of said third bottom flap, said tab extending beyond the edge of the adjacent first bottom flap when the first and third flaps are adhesively secured together, said tab and the adjacent edge of the first bottom flap cooperating to form a notch, and the outer part of the second bottom flap being secured to the fourth bottom flap of the second pair having a hook at its extremity and a narrow slit adjacent thereto opening toward said tab as the carton is erected and not adhered to the adjacent bottom flap whereby expansion of the carton causes said third and fourth bottom flaps to move toward each other as they approach parallel 10 relation, one above the other, and said tab and slit approach each other with the tab passing through said slit and lying behind said hook and between said second and fourth flaps when the bottom of said carton is closed.
